US00D975801S

(12) **United States Design Patent** (10) **Patent No.:** **US D975,801 S**
Liu (45) **Date of Patent:** **** Jan. 17, 2023**

(54) **WATER GUN**

(71) Applicant: **Shunxiong Liu**, Shantou (CN)

(72) Inventor: **Shunxiong Liu**, Shantou (CN)

(**) Term: **15 Years**

(21) Appl. No.: **29/792,856**

(22) Filed: **Apr. 27, 2022**

(51) LOC (14) Cl. **21-01**

(52) U.S. Cl.

USPC **D21/572**; D21/573

(57) **CLAIM**

The ornamental design for a water gun, as shown and
described.

DESCRIPTION

FIG. 1 is a perspective view of a water gun showing my new
design;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom plan view thereof.

(Continued)

The dashed broken lines in the figures depict portions of the water gun that form no part of the claimed design.

1 Claim, 7 Drawing Sheets
